US00D840999S

(12) **United States Design Patent** (10) **Patent No.:** **US D840,999 S**
(45) **Date of Patent:** **** Feb. 19, 2019**

(54) **STAND FOR MOBILE PHONE HOLDER**

(71) Applicants: **MPOW TECHNOLOGY CO., LIMITED**, Hong Kong (HK); **DONGGUAN CHUANG LONG ELECTRONICS LTD**, Dongguan (CN)

(72) Inventor: **Zaihui Hu**, Shenzhen (CN)

(73) Assignees: **MPOW TECHNOLOGY CO., LIMITED**, Hong Kong (HK); **DONGGUAN CHUANG LONG ELECTRONICS LTD**, Dongguan (CN)

(**) Term: **15 Years**

(21) Appl. No.: **29/655,538**

(22) Filed: **Jul. 4, 2018**

(51) **LOC (11) Cl. 14-03**

(52) **U.S. Cl.**

USPC **D14/253**

(58) **Field of Classification Search**

USPC D14/253, 251, 252, 447, 451, 452, 440, D14/434, 458, 432, 439, 457, 460, 238.1, D14/140, 142, 149, 217, 148, 140.8, D14/140.11, 209.1, 151, 140.9, 250, 238; D13/107, 108; D12/415, 223, 114, 420,

(57) **CLAIM**

The ornamental design for a stand for mobile phone holder, as shown and described.

DESCRIPTION

FIG. 1 is a top-front-left perspective view of a stand for mobile phone holder showing my new design; FIG. 2 is a bottom-front perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; FIG. 9 is another bottom-front perspective view of the stand for mobile phone of the present design showing the claimed design in environment in which it may be used; and, FIG. 10 is another top-front-left perspective view of the stand for mobile phone of the present design showing the claimed design in environment in which it may be used. The broken lines shown within solid line disclosure depict portions of the stand for mobile phone holder that form no part of the claimed design. The broken lines shown only in FIG. 9 and FIG. 10 depict environmental subject matter that forms no part of the claimed design.

1 Claim, 9 Drawing Sheets
